UNITED STATES PATENT OFFICE.

DAVID F. NISBET, OF CRAFTON, PENNSYLVANIA.

ROLLING-MILL APPLIANCE.

1,038,421.

Specification of Letters Patent. Patented Sept. 10, 1912.

Application filed October 6, 1909. Serial No. 521,416.

To all whom it may concern:

Be it known that I, DAVID F. NISBET, citizen of the United States, residing at Crafton, in the county of Allegheny and State 5 of Pennsylvania, have invented certain new and useful Improvements in Rolling-Mill Appliances; and I do hereby declare the following to be a full, clear, and exact description of the invention, such as will enable others skilled in the art to which it 10 appertains to make and use the same.

My invention relates to improvements in the type of rolling mill appliances usually known as manipulators, the purpose of 15 which is to arrange an ingot, slab, billet or bar in proper position on the feed tables to enter the desired pass.

The object of my invention is, not only to provide a means for the alinement of 20 the ingot, slab, billet or bar in its proper position in front of the pass, but to turn the ingot, slab or billet so as to present fresh surfaces to the action of the rolls, and more particularly to upturn on edge comparatively wide and thin slabs and hold them in 25 position for edging on either or both sides of the mill.

Another object of my invention is to provide an appliance for rolling mills whereby 30 the ingot, slab or billet, after having passed through the rolls, can be held in position for a return pass through the same groove, or be shifted to other grooves, independently of the mechanism on the leading side 35 of the mill, and which also, when necessary, can be operated so as to move the side guards on the following or catcher's side of the mill, so that they will approximately register with the side guards on the leading 40 or roller's side of the mill, so that in the case of a wide slab on edge, the slab, after passing through the rolls from the leading side of the mill will enter between the side guards on following side, and be maintained 45 in its edgewise position for the return pass.

I am aware that mechanism has been devised for operating the side guards of mill tables for accomplishing this latter purpose, but these are so devised and constructed as 50 to move all the side guards simultaneously, which is not only unnecessary when rolling some classes of material, but also consumes power uselessly and entails unnecessary wear.

55 A further object is to provide a manipulator that is simple and efficient, and in

which none of the working parts are located in pits beneath the table where they are to a degree inaccessible, and are exposed to roll scale, water and other detrius.

In the accompanying drawings, Figure 1 is the plan view of a portion of the rolling mill and tables to which my invention is applicable. Fig. 2 is a transverse section of the tables and manipulator on line "a a" 60 of Fig. 1; Fig. 3 is a transverse section of the table on line "b b" of Fig. 1, and a side elevation of the moving side guards; Fig. 4 shows my manipulator in the two extreme lifting and pushing positions; Fig. 5 is a 65 modification of the manipulator, showing a different method of compelling the manipulator head to travel parallel to the rolls.

"1" represents the roll mounted in the 70 housings, 2 2; 3 3, etc., represent the rollers 75 in the feed-tables on one side of the mill and 4 4, etc., the rollers in the opposite feed table. Above the feed-table rollers 3, there is shown the movable side guard 5, which is attached to the beams 6 6, which are slidably mounted in the oscillating guides 7 7. The oscillating guides 7 7 are pivotally 80 mounted in the bearings 8 8, and are subject to constrained movement in a vertical plane, by means, in this case, of the hydraulic cylinders 16 16; any other motive force, however, may be substituted.

9 is an operating shaft which has an oscillating movement controlled by the motive cylinders 14 and 15 through the links 13 90 and lever arms 12. On the ends of the shaft 9, there are lever arms 10; 11 11 are connecting rods, which connect the levers 10 to the moving guard 5. 17 is a cam also mounted on the shaft 9.

18 are friction rollers mounted on the oscillating guides 7 7.

19 is a shaft extending from table 3 on one side of the mill to table 4 on the opposite side.

20 is a link connecting one of the lever arms 10 to the lever arm 22, transmitting motion to the shaft 19, thence through the lever arm 23 to a slotted stop link 21, which operates on the pin 24 on the lever arm 25.

26 is an oscillating shaft to which is keyed the levers 25 and 27, and is operated through the links 44 44 by the motive cylinders 28 and 29 or other power. To the upper ends of levers 25 and 27 are attached 110 connecting rods 30 30 for actuating the side guard 31. The side guards 31, 32 and 33

have only a horizontal travel, and the construction and operating mechanism is similar, except as stated hereafter.

34 is a shaft operated by the cylinders 37 and 38, or other actuating medium, and through mechanism as heretofore described operates the side guard 33. This shaft extends to the opposite side of the mill where a similar mechanism is located for operating the side guard 32, by means of the cylinder 39 and 40.

35 is a lever arm attached to 34 and at its end is provided with a lug or projection 42 extended toward the lever 36 which also has 15 a projection 43 extending toward the lever arm 35, the lugs or projections so arranged as to interfere and act as stops when in certain positions.

The operation of my invention is as follows: For convenience of description, I have 20 designated the entire mechanism of the manipulator A and the moving side guard mechanism on the opposite side of the table B, and the apparatus on the opposite side 25 of the mill C and D. The side guard 5, it will be noted, has at its lower side, extension 5^b extending downward between the rollers 33, these extensions having a curved contour, the upper terminus of which is in 30 front of the side guard and forms the shelf-like projection 5^a. When it is desired to turn an ingot, slab or billet, the side guard 5 is moved by the cylinder 14 over to the piece to be turned, when the shelf 5^a is beneath the piece, the cylinders 16 are brought 35 into action, lifting the side guard 5, shelf 5^a and carrying with it the piece to be turned, following up horizontally by means of the cylinder 14, and placing the piece in position 40 for rolling by means of mechanism A and B.

The functions of the cam 17 and friction roller 18 are to cause the moving head 5 to travel across the table parallel to the rollers, 45 when the head is in an elevated position. A modified form of my invention, embodying the same principle, is shown in Fig. 5, the function of the cam being performed in this case by the stationary guide 46, which limits 50 the vertical travel of the roller 45, and consequently the oscillation of the guide 7, the movement of the head 5 being the same as in the preferred form of appliance hereinbefore described.

55 When rolling blooms or billets, it is seldom necessary to have recourse to moving side guards on the opposite side of the mill, but when rolling wide thin slabs on edge, it is very essential that means be provided for 60 upturning and holding them on edge in line with the pass on both sides of the mill during the edging process, so as to secure the proper width. To secure this desideratum, whereby the moving guards of C and D can 65 be used only when necessary, and when

necessary moved over to positions substantially in alignment with the moving guards of A and B, I show two methods, both involving identical principles, but somewhat different in mechanism, either or both of which may be used as may be indicated by the conditions of installation.

First describing the operation of A and C: When the moving guard 5 is moved transversely, the shaft 9 through the lever 10, link 20 and lever 22 moves the shaft 19 in unison with the shaft 9. On the shaft 19 at the end near mechanism C is the lever 23, to which is attached a slotted stop link 21, which encompasses a pin 24 on the lever 25 of mechanism C. The length of the slot in the link 21 is equal to the travel of the lever arm 23 at the point of connection to the stop link 21. Therefore, when the moving guide 5 is stopped at any predetermined position, the moving guard 31 of mechanism C will remain at rest, but if it is desired to bring 31 in substantial alignment with 5, water is admitted into the cylinder 28 of mechanism C, which will force the guard 31 to move 90 over until the pin 24 comes in contact with the end of the slotted stop link 21, and there will stop because the cylinder 15 of mechanism A is of practically the same area as cylinder 28 of mechanism C. In practice, I 95 put cylinders 15 and 29 on a constant pressure line and make 14 large enough to overcome 15, and 28 large enough to overcome 29.

The operation of mechanism B and D is 100 as follows: The shaft 34 extends to a point near to the end of the operating shaft 41 of mechanism D, and is in substantial alignment with it. On the adjacent ends of the shafts 34 and 41 are the lever arms 35 and 36, having interlocking lugs or projections 42 and 43, the lug 42 being in front or toward the mill with reference to 43. When the guard 33 of mechanism B is stopped at any given point, the shaft 34 carries the arm 35 and lug 42 with it and it is evident that if the guard 32 of mechanism D is moved over, it can only move to a point where the lug 43 will make contact with the lug 42, and there stop, since, as in the case of mechanisms A and C the pressures in the cylinders 37 and 40 oppose each other and form an equilibrium.

110 Although the description of the mechanism and operation has been confined largely to that of a manipulator for blooming mills, I do not intend to limit its application to this practice, as for instance I can use it in whole or part on bar mills, and by shortening the downwardly projecting lugs on the moving guard 5 and changing the shape, I can not only push a bar or billet over a table, but can reach over it and pull it back.

115 Changes within the scope of the appended claims may be made in the details of con- 130

struction, and other sources of power may be used without departing from the spirit and scope of my invention.

Having described my invention, I claim:

5 1. A rolling mill appliance, comprising a roller feed-table of a rolling mill, a longitudinal side-guard adapted to move laterally with reference to said roller feed-table, supporting beams attached to the side-guard 10 slidably mounted, trunnioned guides pivotally mounted in stationary bearings to carry the said supporting beams, and means for oscillating the said guides in a vertical plane for the purpose of raising or lowering the 15 said side-guard.

2. A rolling mill appliance comprising roller feed tables, longitudinal side guards adapted to move laterally with reference to the feed tables, means for actuating the 20 said side guards through links attached to levers mounted on an oscillating shaft, beams for supporting the side guards, a trunnioned guide for the supporting beams adapted to oscillate in a vertical plane, 25 means for actuating the said trunnioned guide, and means for compelling the transverse travel of the moving side guard to be approximately parallel to the surface of the rollers of the feed tables when the said side 30 guard is in its raised position.

3. A rolling mill appliance comprising roller feed tables, longitudinal side-guards adapted to move laterally with reference to the feed tables, means for actuating the 35 said side-guards through links attached to levers mounted on an oscillating shaft, beams for supporting the side guards, a trunnioned guide for the supporting beams adapted to oscillate in a vertical plane, 40 means for oscillating the said trunnioned guide, a roller attached near one extremity of the trunnioned guide, and a cam mounted on the said oscillating shaft, of such projection of lobe as will limit the oscillatory 45 movement of the trunnioned guide by con-

tact with the said roller, and of such peripheral contour as will compel the transverse travel of the moving side guard to be approximately parallel to the surface of the rollers of the feed tables when the said side- 50 guard is in its raised position.

4. A rolling mill appliance comprising the feed-tables on each side of a rolling mill, side-guards mounted above each table, mechanism whereby each side-guard can be 55 moved transversely to the tables, a shaft operated by the actuating power of the appliance on one side of the mill and extending to the appliance on the opposite side of the mill, terminating with a lever-arm and a 60 slotted link attached to the said lever-arm, adapted to engage a member on the actuating mechanism of the appliance on the opposite side of the mill, whereby the transverse travel of the side-guard on one side of the 65 mill can be restricted to that of the side-guard of the other side of the mill, thereby bringing them in approximate alinement.

5. A rolling mill appliance comprising the feed-tables on each side of a mill, laterally movable side-guards mounted above each side of each table, mechanism whereby each side-guard can be moved laterally, a shaft operated by the actuating power of the appliance on one side of the mill and extending 70 to the appliance on the opposite side of the mill, a lever-arm on said shaft, a lever-arm on the operating shaft of the second appliance, and a lug or projection on said second lever-arm, adapted to engage and act as a 75 stop to limit the travel of the side-guard to that of its mate on the opposite side of the mill.

In testimony whereof, I have signed my name to this specification in the presence of two subscribing witnesses.
